CLAIM

The ornamental design for a luminaire, as shown and described.

DESCRIPTION

FIG. 1 is a top-left-rear perspective view of a representative embodiment of a luminaire according to our new design;
 FIG. 2 is a front elevational view thereof;
 FIG. 3 is a rear elevational view thereof;
 FIG. 4 is a top plan view thereof;
 FIG. 5 is a bottom plan view thereof;
 FIG. 6 is a right side elevational view thereof; and,
 FIG. 7 is a left side elevational view thereof.

The dashed broken lines in the drawings show portions of the luminaire that form no part of the claimed design.
